UNITED STATES PATENT OFFICE.

CHARLES W. HARROLD, OF CLEVELAND, OHIO, ASSIGNOR TO THE HARRIS AUTOMATIC PRESS COMPANY, OF CLEVELAND, OHIO, A CORPORATION OF OHIO.

PRINTING PRESS.

Application filed May 20, 1922. Serial No. 562,391.

To all whom it may concern:

Be it known that I, CHARLES W. HARROLD, a citizen of the United States, residing in the city of Cleveland, in the county of Cuyahoga and State of Ohio, have invented certain new and useful Improvements in Printing Presses, of which the following is a specification, reference being made to the accompanying drawings, forming a part thereof.

My improvement relates more particularly to printing-presses in which there is also embodied a pair of coacting cylinders for cutting, slitting, or otherwise perforating the successive sheets of stock after same have been printed in the printing couple proper.

The objects of my invention are, among other things, to provide a simplified press of this type in which an intermediate transfer-cylinder is arranged between the printing couple and slitting couple combined with means for adjusting the transfer-cylinder or one of the cutting cylinders to properly register the sheet for the slitting operation after the printing in case the printing design on the plate cylinder is not exactly straight with such cylinder so that when the printing appears on the sheet, the side margins are not exactly parallel with the edges of the sheets; further to provide an automatic relay throw-off for the cutting cylinders so timed and coordinated with the impression throw-off for the printing couple that the separation of the cutting cylinders

is delayed until both sheets of stock in the press shall have completed their passage through the cutting cylinders, no matter when the press itself is tripped, either automatically from the absence of a sheet on the feed-board, or manually at some other part of the cylinder, such automatic relay mechanism taking care of the timing of such second throw-off of the cutting cylinders until the last full sheet will be completely slit or

cut before the slitting or cutting cylinders separate; further to provide means for individual as well as collective adjustments of the cutting disks on the main shaft of the male cutting cylinder whereby the individual blades may be readily set to obtain accurate cutting or slitting; further to provide novel means for mounting such individual blades allowing for shifting or easy removal of same combined with means for procuring minute relative adjustments for

the several blades, as well as separate blade adjustments in their individual carriers.

My improved printing-press also embodies other features of novelty and improvement in combination with a slitting, cutting or perforating attachment, whereby the operating mechanisms are simplified and made more effective and otherwise better adapted for use, all of which will be herein-after set forth and then particularly pointed out in the appended claims.

The drawings show my invention in its preferred embodiment in a three cylinder offset press with the slitting cylinder attachment arranged with blades adapted to slit or cut a sheet or strip of cardboard or similar stock with eight rows across the sheet requiring seven knives or blades in each row. Such layout for the cutting blades, however, may be widely varied to meet requirements. My improvements, however, are not to be restricted to any particular type of printing-press, since the invention may be embodied in various types with the same advantages and results.

Of the drawings, Fig. 1 is a diagrammatic view in side elevation, of an offset printing-press embodying my improvements and particularly illustrating the layout of the cylinders;

Fig. 2 is an enlarged detail sectional view illustrating a form of sheet detector that may be used to automatically trip the impression throw-off;

Fig. 3 is an end view looking from the left in Fig. 1 illustrating more particularly the slitting cylinders and relay throw-off device for the male slitting cylinder;

Fig. 4 is an enlarged end view of the throw off relay mechanism the operating arms thereof being broken off;

Fig. 5 is a top plan view of the mechanism shown in Fig. 4;

Fig. 6 is a sectional view the section being taken on line 6—6 in Fig. 5;

Fig. 7 is a fragmentary end view illustrating condition of relay mechanism after the impression-cylinder has been thrown off;

Fig. 8 is a diagrammatic sectional view, the section being taken on line 8—8 in Fig. 5 illustrating position of first pawl when impression-cylinder has been thrown off;

Fig. 9 is a view similar to Fig. 8 illustrating the first ratchet plate as having been shifted by its cooperating pawl;

Fig. 10 is a diagrammatic sectional view, the section being taken on line 10—10 in Fig. 5 looking in the direction of the arrow;

5 Figs. 11 and 12 are diagrammatic sectional views showing the respective positions of second ratchet plate before and after the shaft for operating the throw-off for the male slitting cylinder has been shifted;

10 Fig. 13 is a detail side view of one of the disks which compose the male slitting cylinder, the clamps for holding the blades being omitted;

15 Fig. 14 is a detail side view illustrating male and female slitting cylinders.

16 Fig. 15 is a fragmentary sectional side view, looking from the left in Fig. 14, the female cylinder being broken off, the section being taken on line 15—15 on Fig. 14;

20 Fig. 16 is an enlarged sectional detail view of a portion of a disk for the male slitting cylinder, illustrating the means to retain the blades therein;

25 Fig. 17 is a fragmentary face view illustrating a portion of the female slitting cylinder and the associated bed-plates for the blades carried by the disks on the male slitting cylinder;

30 Fig. 18 is a detail view illustrating the arrangement of the gears on the several cylinders and also the specific nature of the gears;

35 Fig. 19 is an end view looking from the left in Fig. 18, the gears for the slitting cylinders being omitted; and

35 Figs. 20 and 21 are detail views taken on lines 20—20 and 21—21 respectively in Fig. 18.

Similar numerals refer to similar parts throughout the several figures.

40 Referring more particularly to Fig. 1, the frame 22 supports the bearings for the form-cylinder 23, the rubber blanket-cylinder 24 and impression-cylinder 25, these cylinders being mounted on the shafts 26, 45 27 and 28 respectively. These three cylinders are so constructed and arranged in the frame 22 that the blanket-cylinder 24 forms a printing couple with the impression-cylinder 25, after receiving its design from the form-cylinder 23. The respective cylinders have each fixed thereto suitable gears the pitch-diameters of which coincide with the peripheries of the respective cylinders. Referring to Figs. 18 50 and 21, the blanket-cylinder 24 carries the gear 29 adjustably secured to the cylinder 24 by screw bolts 30 passing through slots 31; the gear 29 enmeshes with the gear 32 adjustably secured to the impression-cylinder 25 by screw-bolts 33 passing through slots 34. Concentrically mounted on the gear 32 is the slip-gear 35 which is adjustable on the gear 32 by the screw-bolts 36 passing through slots 37 (Figs. 18 and 19), 60 the gear 35 also enmeshing with the gear

29. Such arrangement of gears for the blanket-cylinder 24 and impression-cylinder 25 takes up all looseness or play between the cylinders resulting in accuracy in the printing operation. The gears for three 70 cylinders 23, 24 and 25 intermesh to form the driving mechanism to secure the proper rotation of these cylinders in the directions shown by the arrows on the three cylinders in Fig. 1. Power is derived from the main 75 driving shaft 38 carrying the pinion 39 in engagement with the gear 29.

The shaft 27 carrying the blanket-cylinder 24 is mounted at both ends in the eccentric bearings 40, which, in turn, are mounted in 80 journals 41 secured to the frame 22. The bearings 40 have arms 42 projecting from flanges on the outside of the frame 22 as shown on one side thereof, such arm 42 being connected to the arm 43 secured to the 85 spring-impelled throw-off shaft 44 by the link 45, the shaft 44 being rocked by the spring 46 in the direction of the arrow shown in Fig. 2 to pull the link 45 and arm 42 to the right to separate the blanket-cylinder 24 from both form-cylinder 23 and impression-cylinder 25 to throw off the printing impression. A reverse movement 90 of the link 45 will restore the impression by rotating the shaft 44 in a clockwise direction 95 by a hand lever which is not here shown since such device is well-known in the art.

In order that this impression throw-off and throw-on mechanism may be automatically actuated in case of the failure of the 100 feed of a sheet to the press, I have devised the following mechanism shown in Figs. 1 and 2: The feed-table 47 is secured to the frame 22 whereon the successive sheets may be advanced to the impression-cylinder 25 as 105 shown in Fig. 1. Extending transversely in the frame 22 is the throw-off shaft 44 which is oscillated by the spring 46 as heretofore described. The shaft 44 is held in the position shown by the latch 48 secured to the shaft 49 journalled in the frame 22 and extending across the feed-table 47 as shown in Fig. 2. The latch 48 engages with the notch 50 in the collar 51 mounted on the shaft 44. Preferably this latch 48 is released automatically through trip mechanism on the feeder: The feed-table 47 supports the stock 52 that is being fed to the press. Extending transversely above the feed-table 47 and journalled in uprights at the sides thereof is the shaft 53 which carries the arm 54 (Fig. 1) connected by the link 55 to the crankpin 56 on the impression-cylinder shaft 25 so as to impart to the shaft 53 an oscillating movement. 57, 57 are two grooved collars rigidly secured to the shaft 53. Adjacent each grooved collar 57 is the disk 58 affixed to the inner end of the tubular shaft 59 which is loosely sleeved on, and encloses a portion of, the shaft 53 as shown in Fig. 2. The 110 115 120 125 130

- tubular shaft 59 carries the arm 60 having the projecting lug 61 which engages with the arm 62 secured to the shaft 49. The trip-lever 63 is pivoted at 64 between the parallel 5 sides of the grooved collars 57, so that its longer and heavier arm is held from falling into the aperture 65 cut in the top of the feed-table 47 by the interposition of the stock 52 as shown in Fig. 2. The opposite end of 10 the lever 63 is T-shaped to form the laterally extending tooth 66; in the peripheries of the collars 57 and also of the disk 58 are formed cut-outs 67 and 68 respectively. Ordinarily the tooth 66 rests against, or is in proximity 15 to, the periphery of the disk 58; it can engage with the cut-out 67 of the collars 57 only when it can fall into the cut-out 68 of the disk 58. When this occurs the disk 58 with its tubular shaft 59, which are normally 20 at rest, are locked to, and turn with, the oscillating shaft 53. The entrance of this tooth 66 into locking engagement with the disk 58 will occur upon the failure or interruption in the feed supply. When the stock 25 52 is in proper position as shown in Figs. 1 and 2, the curved longer arm of the trip-lever 63 will engage therewith and will be prevented from lowering into the aperture 65, and from turning sufficiently to interlock the disk 58. If the stock 52 should, 30 at any time, be interrupted or absent, the longer arm of the trip-lever 63 will fall of its own weight into the aperture 65, thereby causing the tooth 66 to interlock with the 35 cut-out 68 of the disk 58. Thus the tubular shaft 59 will be caused to oscillate with the shaft 53 to lift the arm 60 to release the latch 48 engaging the notch 50 in the collar 51 on the shaft 44. Through this movement of the 40 herein described mechanism the shaft 44 is partially rotated by the spring 46 to throw-off the impression by separating the blanket-cylinder 24 from the form-cylinder 23 and impression-cylinder 25, all controlled automatically by the stock. 45
- Means are provided to adjust the position of the impression-cylinder 25 with relation to the blanket-cylinder 24 to accommodate sheets of stock of different thickness: Refer- 50 ring to Fig. 1 the impression-cylinder shaft 28 is mounted at both ends in eccentric bearings 69, which, in turn, are mounted in journals 70 secured in the frame 22. The bearings 69 carry the arm 71 projecting from 55 flanges outside the frame 22, as shown on one side thereof, and the screw-bolt 72 carried by the arm 71 and passing through curved slots 73 enable adjustments of the impression-cylinder 25 by moving same horizontally to 60 and from the blanket-cylinder without disturbing its relation to the transfer-cylinder 74 mounted on the shaft 75 journaled in the bearings 76 horizontally slidable in the frame 22 by the adjusting screws 77 and 78. 65 The transfer-cylinder 74 carries the suc- 70 75 80 85 90 95 100 105 110 115 120 125 130
- sive printed sheets to the female cutting cylinder 79 mounted on the shaft 80 journaled in the bearings 80^a vertically slidable in frame 22 by the adjusting screws 80^b and 80^c, which cylinder 79 coacts with the male cutting-cylinder 81 to form a slitting or cutting couple; the sheets are taken by the delivery cylinder 82 and intermediate cylinder 83 to the delivery-mechanism 84. Referring to Fig. 18, the cutting cylinder 79 adjustably carries the gear 85 which meshes with both the slip gear 86 and the main gear 87 adjustably mounted on the cylinder 81, the slip-gear 86 being adjustable on the gear 87, such arrangement of gears for the cylinders 79 and 81 with screw-bolt and slot devices for adjustment having been heretofore described with reference to the blanket-cylinder 24 and impression-cylinder 25 respectively. The cutting cylinders 79 and 81 are rotated by means of the pinion 88 in mesh with the gear 85 and pinion 39 on the main driving shaft 38.
- Referring to Figs. 3 and 15, the male cutting cylinder 81 is preferably composed of a series of disks 89 slidably mounted on the shaft 90 of the cylinder 81, and preferably secured thereto by set screws which are not shown. Each disk 89 has formed therein a clearance hole 91 to receive a transverse screw-threaded rod 92 on which screw-nuts 93 and 94 are carried on either side of the several disks 89 as shown in Figures 3 and 15. Means are preferably employed to collectively adjust the several disks 89 on the shaft 90, which means may be widely varied in construction. In the present embodiment, two bearing disks 89^a are pinned fast to the shaft 90 at either end as shown in Fig. 3, each disk 89^a having a clearance hole 95 through which the ends of the rod 92 project, such rod carrying the nuts 93^a and 94^a on either side of the disks 89^a as shown. When it is desired to collectively adjust the disks 89 as a unit, the two sets of nuts 93^a and 94^a are manipulated to shift the rod 92 transversely in either direction, while a group adjustment of several disks 89 is attained by loosening the nuts 93 and 94 of the remaining disks and then tightening 105 the same after the first set of disks has been shifted as a group. Each disk 89 may be separately adjusted relatively to its adjacent disks by the sets of nuts 93 and 94 on either side of the disk to be shifted. 110
- Other means for collectively adjusting the disks 89 may be employed, as for example, placing keyed washers and threaded collars on the projecting threaded ends of the shaft 90 outside the frames 22 which 115 will shift the entire cylinder 81 laterally as a unit in the direction desired.
- Separate means are provided to throw off the cylinder 81 from the cylinder 79. Accordingly the shaft 90 for the male cutting 120 125 130

cylinder 81 is mounted at both ends in eccentric bearings 95 (Figs. 1 and 3) which, in turn are mounted in journals 96 carried by the frame 22. The bearings 95 carry the 5 projecting arms 97 (Fig. 3) to which is pivotally secured the toggle levers 98 pinned at 99 to the toggle arms 100 mounted on the throw-off shaft 101 journalled in the brackets 102 secured to the frame 22 as 10 shown in Fig. 3.

An important feature of my invention is to provide an automatic relay mechanism by which the impression throw-off for the printing couple inauguates and controls the 15 throw-off for the cutting or slitting cylinders in predetermined sequence with the impression throw-off, so that each of the sheets in the press at the time the press is tripped (either automatically or by hand) may be 20 fully printed and thereafter slitted or cut by the cylinders 79 and 81 before the latter cylinders separate. Referring to Figs. 1 and 3 and to detail Figs. 4 to 12 inclusive, I have devised a relay mechanism by which 25 the separation of the cutting cylinders 79 and 81 is delayed, after the separation of the cylinder 24 from the cylinders 23 and 25, until the last sheet properly fed to the press has completely passed through the cutting cylinders, such relay mechanism automatically taking care of the timing of such 30 second throw-off of the cylinders 79 and 81 until this last full sheet has been completely slit or cut by such cylinders. Such relay 35 mechanism is described as follows: The throw-off shaft 101 on one side of the frame 22 as shown in Fig. 3 carries two coacting cam-arms 103 and 104 mounted on sleeves 105 and 106 respectively, both being journalled on the shaft 101. Between the two 40 arms 103 and 104 is arranged the cam 107 secured to the cylinder shaft 90; the arms 103 and 104 carry the cam-rollers 108 and 109 respectively to engage with the cam 107 by means of the spring 110 connecting the 45 arms 103 and 104. In the normal operation of the press the arms 103 and 104 are idling and are rocked up and down by the cam 107 in scissor-like fashion, the spring 110 maintaining the rollers 108 and 109 always in 50 contact with the cam 107 with the arm 103 always above and the arm 104 always below the low part of the cam 107.

Referring more particularly to Figs. 4, 5 and 6 the sleeve 105 carries the bracket 111 on which the pawl 112 is pivoted; the pawl 112 has extending outwardly therefrom the pin 113 on which the cam-roller 114 is rotatably mounted to ride on the top 60 of the cam-plate 115 journalled on the shaft 101. Adjacent the cam-plate 115 and pinned thereto is the rock-arm 116 journalled on the end of the shaft 101 and secured thereto by the washer 117. Inwardly and 65 adjacent the sleeve 105 the single-tooth

ratchet-plate 118 is arranged beneath the pawl 112 and is pinned to the cam-plate 119, both ratchet and cam being journalled on the shaft 101 and arranged thereon between the sleeves 105 and 106 as shown in 70 Fig. 6. The cam-plate 119 carries the transverse rod 120 which projects outwardly and extends through the slot 121 formed in the rock arm 116 as shown in Figs. 6 and 7. Inwardly adjoining the sleeve 106 is the 75 single-tooth ratchet-plate 122 mounted on the shaft 101 and is also pinned to the collar 123 which is secured to the shaft 101 by the bolt 124, the collar 123 also carrying the hand-lever 125, as shown in 80 Figs. 5 and 6. The sleeve 106 carries the bracket 126 (Figs. 5 and 11) on which the pawl 127 is pivoted to coact with the ratchet-plate 122. Extending outwardly from the pawl 127 is the pin 128 (Fig. 5), on 85 which is rotatably mounted the cam-roller 129 which is adapted to ride on the top of the cam-plate 119. The lower end of the rock-arm 116 has pivoted thereto the link 130 which is also pivotally secured by the 90 pin 131 to the arm 42 projecting from the eccentric bearings 40 for the blanket-cylinder 24.

Means are provided for mounting the individual sets of knife blades or cutters on 95 the cutting cylinders 79 and 81 which are shown in detail in Figs. 13 to 17 inclusive, whereby the individual blades may not only be easily removed, but also be secured on the cylinder 81 by means admitting of 100 minute relative adjustments. Referring to Figs. 15 and 16, the disks 89 on the male cutting cylinder carry the split housings 132, the successive housings 132 being adjusted relatively to one another by the screws 105 134 (Fig. 16). Each housing 132 has the cut-out 135 formed in its outer surface to contain and hold the transverse cutter blades 136 maintained between the clamp blocks 137 and 138. The block 138 has a bevel 110 surface 139 on which the wedge block 140 slides inwardly to bind the blades 136 between the blocks 137 and 138. The block 140 has a hole bored therein through which the screw-bolt 141 extends to engage with the housing 132. The spring 142 is coiled around the bolt 141 and tends to force the wedge block 140 outwardly. The inward movement of this block 140 by screwing in the bolt 141 against the spring 142 binds the 120 blades 136 in position. The longitudinal cutter blades 143 are carried in a suitable groove 144 formed in the periphery of plates 158 on the disks 89, and are adjusted relatively to one another in the grooves 144 125 by the screws 159 (Fig. 17). The female cutting cylinder 79 has formed in its outer surface circular parallel run-ways 145 in which are adjustably secured the groove bed-plates 146 to coact with the longitudinal 130

cutting blades 143: in like manner the grooved-bed-plates 147 are also adjustably secured to the cylinder 79 to receive the transverse cutting blades 136, all as shown in Fig. 17. The collective arrangement of the two sets of cutting blades 136 and 143 in relation to the female cutting cylinder 79 is shown in Figs. 13 and 14.

In order that the transfer-cylinder 74 may transmit the printed sheet from the impression-cylinder 25 to the cutting cylinder 79 so that such sheet may be positioned and timed to secure great accuracy in the slitting operation, I have devised means where-
15 by coacting register racks are adjustably carried by the cylinders 74 and 79 at the time the sheet is transferred which are best shown in Figs. 18 to 20: The gear 148 co-acts with the gear 32 and gear 85, and is ad-
20 justably mounted on the transfer-cylinder 74 by screw bolts 149 passing through washers 150 and slots 151. The teeth on this gear 148 are undercut considerably so that it is not driven by the gear 32 except when
25 the register rack 152 adjustably secured to the gear 148 by screw-bolts 153 passing through slots 154 (Figs. 18 and 20) is in mesh with the gears 32 and 35 on the impres-
sion-cylinder 25 while receiving the sheet
30 from such impression cylinder 25. At other periods in the rotation of the cylinder the gear 148 practically floats between the impression-cylinder gears and the gear 85 on the cylinder 79 until the register rack 152
35 meshes with a similar rack 155 adjustably secured to the gear 85 by bolts 156 passing through slots 157 in the same manner as the rack 152 is mounted on the gear 148 (Fig. 20). By this mechanism the coact-
40 ing register racks 152 and 155 fully control the timing of the transfer-cylinder 74 at both periods when receiving the sheet, and thereafter when delivering same to the female cutting cylinder 79.

45 The operation of the hereinbefore described mechanism is substantially as follows: Whenever the stock 52 is interrupted or is absent from the feed-table 47, the trip-lever 63 acts to release the spring-impelled shaft 44 which pulls the link 45 to the right as indicated by the arrow in Fig. 1, thereby swinging the arm 42 also to the right to separate the blanket-cylinder 24 from both form-cylinder 23 and impression-cylinder 25
50 to throw-off the impression. When the arm 42 moves to the right it simultaneously pulls the link 130 with it in the direction of the arrow thereby shifting the rock-arm 116 and its attached cam-plate 115 from the position shown in Fig. 4 to that shown in Fig. 7. This anti-clockwise movement allows the pawl 112 to engage the tooth in the ratchet-plate 118. At the next upward movement of the arm 103 by the cam 107 on the cylinder-shaft
60 90 the ratchet-plate 118 is swung to the left as

shown in Fig. 9 thereby moving the cam-plate 119 from the dotted line to the full line position shown in Fig. 9. This movement will cause the cam-roller 129 to ride off the high part of the cam-plate 119 and the pawl 127 will engage the tooth on the ratchet-plate 122 as shown in Figs. 10 and 11. When the arm 104 is thereafter depressed by the cam 107 the ratchet-plate 122 and shaft 101 will be rocked in a clockwise direction to break the toggle levers 98 and 100 thereby shifting the eccentric bearings 95 to separate the male cutting cylinder 81 from both the female cutting cylinder 79 and delivery-cylinder 82. The hand lever 125 may also be used to throw-off the cutting cylinders independently of the impression throw-off, and this hand lever 125 is also used to restore the cutting cylinders to operative position. The hand-lever (not shown) on the shaft 44 may also be used to restore the impression throw-off, reset the latch 48 for the automatic trip mechanism, and raise the pawl 112 out of engagement with the ratchet 118 so that the arms 103 and 104 are again free to be raised and lowered by the cam 107 without inaugurate-
70 75 80 85 90 95 100 105 110 115 120 125 130

By this construction I have devised two automatic sequential throw-offs for the printing couple and slitting couple, the second throw-off being positively actuated by means operable through the continued movement of the press, the cutting or slitting cylinder throw-off being controlled, but not operated, by the impression throw-off with the timing of such second throw-off being delayed until both sheets in the press will have passed completely through the cutting cylinders before the latter are separated, no matter at what part of the cycle the impression of the printing couple is thrown-off either automatically by the feeder-trip devices or manually by the operator.

The horizontal sliding bearings 76 for the transfer-cylinder 74 at both ends thereof provide a ready means for allowing for any inaccuracy of the printing design on the form-cylinder 23, such inaccuracy being thereafter carried forward to the cutting cylinders 79 and 81 with a similar inaccuracy in the cutting margin. By properly adjusting one or the other of such slideable bearings 76, the sheet is delivered by the cylinder 74 to the cutting cylinder 79 so that the printed design is square with the cylinder, and the knife cuts made by the blades 136 and 143 fall in proper register with the printed margin of the sheet; in like manner the cylinder 79 may be vertically adjusted by shifting the bearings 80 for the same purpose.

I claim as my invention:

1. In a printing-press having two mem- 130

bers constituting a printing couple, a slitting couple, means for carrying a sheet from the printing couple to the slitting couple, and means for shifting the sheet-carrying 5 means to register the sheet in the slitting couple.

2. In a printing-press having two members constituting a printing couple, a slitting couple, means for carrying a sheet 10 through said couples, and means for adjusting said carrying-means to register the sheet in the slitting couple.

3. In a printing-press having two members constituting a printing couple, a slitting couple, a transfer-cylinder intermediate 15 said couples to carry a sheet from the printing couple to the slitting couple, and means for adjusting such cylinder to register the sheet for the slitting couple.

4. In a printing-press having two members constituting a printing couple, a slitting couple, a transfer-cylinder intermediate 20 said couples, and means for variably adjusting such cylinder to register the sheet 25 for the slitting couple.

5. In a printing-press having two members constituting a printing couple, a slitting couple, a transfer-cylinder intermediate 30 said couple, and means for adjusting such cylinder at either end to register the sheet 35 for the slitting couple.

6. In a printing-press having two members constituting a printing couple, a slitting couple, a transfer-cylinder intermediate 35 said couples, to carry a sheet from the printing couple to the slitting couple, and means for variably adjusting such cylinder to register the sheet for the slitting couple.

7. In a printing-press having two members constituting a printing couple, a slitting couple, a transfer-cylinder intermediate 40 said couples to carry a sheet from the printing couple to the slitting couple, and means for laterally moving such cylinder at either end in relation to such couples to register the printed sheet for the slitting couple.

8. In a printing-press having a printing couple and a slitting couple, a sheet transfer-cylinder intermediate said couples, and 45 coacting registering means carried by said slitting couple and transfer-cylinder to properly present the sheet to said slitting couple.

9. In a printing-press having a printing couple and a slitting couple, a sheet transfer-cylinder intermediate said couples, and coacting registering means adjustably carried by said slitting couple and transfer-cylinder 50 to properly present the sheet to said slitting couple.

10. In a printing-press having printing and impression-cylinders, a pair of slitting cylinders, a sheet transfer-cylinder between 55 the impression-cylinder and a slitting cylin-

der, and coacting registering means carried by each of said cylinders to control the register of said transfer-cylinder when taking the sheet from the impression-cylinder and when thereafter delivering same to the slitting cylinder. 70

11. In a printing-press having printing and impression-cylinders, a pair of slitting cylinders, a sheet transfer-cylinder between the impression-cylinder and a slitting cylinder, and coacting registering means adjustably carried by each of said cylinders to control the register of said transfer-cylinder when taking the sheet from the impression-cylinder and when thereafter delivering 80 same to the slitting cylinder. 75

12. In a printing-press having printing and impression-cylinders, a pair of slitting cylinders, a sheet transfer-cylinder between the impression-cylinder and a slitting cylinder, and coacting registering means separately and adjustably carried by each of said cylinders to control the register of said transfer-cylinder when taking the sheet from the impression-cylinder and when thereafter 90 delivering same to the slitting cylinder. 85

13. In a printing-press having printing and impression-cylinders, a pair of slitting cylinders, a sheet transfer-cylinder between the impression-cylinder and a slitting cylinder, coacting gears on each of the said cylinders to rotate same in unison, and coacting registering means carried by said transfer and slitting cylinders to properly present 95 the sheet to said slitting cylinder. 100

14. In a printing-press having printing and impression-cylinders, a pair of slitting cylinders, a sheet transfer-cylinder between the impression-cylinder and a slitting cylinder, coacting gears on each of said cylinders to rotate same in unison, and coacting registering means carried by said transfer and slitting cylinders to properly present 105 the sheet to said slitting cylinder, said registering means on the transfer-cylinder coacting with the impression-cylinder gear when taking the sheet from the latter. 110

15. In a printing-press having printing and impression-cylinders, a pair of slitting cylinders, a sheet transfer-cylinder between 115 the impression-cylinder and a slitting cylinder, coacting gears on each of said cylinders to rotate same in unison, coacting registering means carried by said transfer and slitting cylinders to properly present the sheet to said slitting cylinder, said registering means on the transfer-cylinder coacting with the impression-cylinder gear when taking the sheet from the latter, and means for 120 separately adjusting said gears and registering means. 125

16. In a printing-press having two members constituting a printing couple, a pair of slitting members, means to throw-off the impression, means to throw-off the slitting 130

members normally held inoperative but placed in operative position by said impression throw-off means.

17. In a printing-press having two members constituting a printing couple, a pair of slitting members, means to throw-off the impression, means to throw-off the slitting members normally held inoperative but placed in operative position by said impression throw-off means at a predetermined point in their cycle.

18. In a printing-press having two members constituting a printing couple, a pair of slitting members, means to throw-off the impression, means to throw-off the slitting members normally held inoperative but placed in operative position by said impression throw-off means at a predetermined point in their cycle after the impression is thrown off.

19. In a printing-press having two members constituting a printing couple, a pair of slitting members, means to throw-off the impression, means to throw-off the slitting members normally held inoperative but placed in operative position by said impression throw-off means by the continued movement of the press.

20. In a printing-press having two members constituting a printing couple, a pair of slitting members, means to throw-off the impression, means to throw-off the slitting members normally held inoperative but placed in operative position by said impression throw-off means at a predetermined point in their cycle by the continued movement of the press.

21. In a printing-press having two members constituting a printing couple, a pair of slitting members, means to throw-off the impression, means to throw-off the slitting members normally held inoperative but placed in operative position by said impression throw-off means at a predetermined point in their cycle after the impression is thrown off by the continued movement of the press.

22. In a printing-press having a plurality of printing members, a pair of slitting members, means for throwing off said slitting members, normally held inoperative, and means for separating two of the printing members to throw off the impression and simultaneously inaugurate the placing of said slitter throw-off means in operative position.

23. In a printing-press having a plurality of printing members, a pair of slitting members, means for throwing off said slitting members normally held inoperative, and means automatically controlled by the stock for separating two of the printing members to throw-off the impression and simultaneously inaugurate the placing of said slitter throw-off means in operative position.

24. In a printing-press having a plurality of printing members, a pair of slitting members, means for throwing off said slitting members normally held inoperative, and means for separating two of the printing members to throw-off the impression and simultaneously inaugurate the subsequent placing of said slitter throw-off means in operative position through the continued movement of the press.

25. In a printing-press having a plurality of printing members, a pair of slitting members, means for throwing off said slitting members normally held inoperative, means for separating two of said printing members to throw off the impression and place said slitter throw-off means in operative position, and means operable by the continued movement of the press to actuate said slitter throw-off.

26. In a printing-press having a plurality of printing members, a pair of slitting members, means for throwing off said slitting members normally held inoperative, means for separating two of said printing members to throw-off the impression and simultaneously place said slitter throw-off means in operative position, and means operable by the continued movement of the press to actuate said slitter throw-off.

27. In a printing-press having a plurality of printing members, a pair of slitting members, means for throwing off said slitting members normally held inoperative, means for separating two of said printing members to throw-off the impression and place said slitter throw-off means in operative position, and means operable by the continued movement of the press to actuate said slitter throw-off in predetermined sequence to said impression throw-off.

28. In a printing-press having a plurality of printing members, a pair of slitting members, means for throwing off said slitting members normally held inoperative, means for separating two of said printing members to throw-off the impression and place said slitter throw-off means in operative position, and means operable by the continued movement of the press to actuate said slitter throw-off at any part of the cycle of operation in predetermined sequence to said impression throw-off.

29. In a printing-press having a plurality of printing members, a pair of slitting members including means to throw-off same normally held inoperative, means to set said slitter throw-off in operative position, and means to actuate said slitter throw-off through the continued movement of the press.

30. In a printing-press having a plurality of printing members, a pair of slitting members including means to throw-off same normally held inoperative, means to set said

slitter throw-off in operative position, and means to actuate said slitter throw-off at a predetermined point in the cycle through the continued movement of the press.

5 31. In a printing-press having two members constituting a printing couple, a pair of slitting members including means for throwing off same, and means controlled by the stock for throwing off the impression 10 having a connection with the slitter throw-off to simultaneously and automatically set the latter for operation after the impression is thrown off.

32. In a printing-press having two members constituting a printing couple, a pair of slitting members including means for throwing off same, and means controlled by the stock for throwing off the impression

having a connection with the slitter throw-off to simultaneously and automatically set 20 the latter for operation after the impression is thrown off through a continued movement of the press.

33. In a printing-press having two members constituting a printing couple, a pair 25 of slitting members including means for throwing off same, and means controlled by the stock for throwing off the impression having a connection with the slitter throw-off to simultaneously and automatically set 30 the latter for operation after the impression is thrown off through a continued movement of the press at a predetermined point in the cycle.

CHARLES W. HARROLD.
